APPARATUS FOR ELECTRICAL USES

Miles L. Svihart, Garden City Park, N. Y., assignor to Western Electric Company, Incorporated, New York, N. Y., a corporation of New York

Application June 21, 1934, Serial No. 731,583

2 Claims. (Cl. 200—152)

This invention relates to an electric switch and more particularly to an electrical switch having means to tiltably and removably retain in place therein a circuit making and breaking device 5 having a relatively frangible body.

An object of the invention is to provide a simple, rugged and reliable switch for securely and removably retaining in place therein in a tiltably cradle a tiltably operable circuit making and 10 breaking device having a relatively delicate and frangible body.

With the above and other objects in view one embodiment of the invention contemplates a switch structure adaptable to be installed in a 15 location within a ceiling or wall or floor member of a telephone booth or closet although it may be in any other appropriate site, and to be actuated by a push rod or other member actuated by the opening and closing movements of a door, the 20 switch in its preferred construction comprising a tiltably cradle having means thereon for securely and removably carrying a sealed glass tube having two fixed electrodes and a body of mercury therein.

25 Other objects and features of the invention will appear from the following detailed description of one embodiment thereof taken in connection with the accompanying drawing in which the same reference numerals are appended to identical 30 parts in the several figures and in which

Fig. 1 is a broken view in perspective of an electric switch embodying the invention mounted on a dome light assembly intended for use in a telephone booth, closet or the like and actuated 35 by an operating rod attached to one of the members of a door hinge;

Fig. 2 is an enlarged broken view in end elevation of the mercury tube cradle;

Fig. 3 is a similar view thereof in side elevation 40 minus the push rod block; and

Fig. 4 is a detached, enlarged view in plan of the mercury switch tube.

In the embodiment of the invention herein disclosed, there is provided a generally rectangular cup like switch housing 20 mounted for convenience on the upper or rear side of the frame 21 of a dome light assembly intended to be installed in the ceiling of a telephone booth in such fashion 45 that the housing will be situated and concealed between the ceiling and the roof of the booth, although the housing may also be placed in any convenient location.

A ring base 22 of insulating material is secured 50 to the floor of the housing 20 as by screws or bolts

23 passing through slots 24 in the base 22. An arcuate connection plate 25 is positioned on the ring 22 and secured thereto by rivets or screws 26. Contact clamp screws 27 and 28 are mounted in the plate 25. One conductor 29 of an electric current supply cable 30 is secured to the plate 25 by the screw 28. The other conductor 31 of the cable 30 is secured by a clamp screw 32 to a second contact plate 35 mounted on the ring 22, and provided with an inwardly extending tongue 10 having a threaded perforation 34. The cable 30 brings electrical current from a source not shown. The plate 35 is also secured on the ring 22 by screws 26. The aperture 34 is connected to a conductor 38 leading to one terminal of a lamp 15 socket of the usual type for holding an electric bulb or lamp not shown but which may be located under the dome like receptacle 40 which is part of the frame 21.

The left hand end (Figure 1) of the plate 25 is, 20 as best shown in Figure 2, bent to form a supporting lug 41 which carries a horizontal pivot pin 42 formed on a stud secured to the lug. A second supporting lug 43 is secured on the ring 22 by a screw 26 entering a horizontal foot 44 integral 25 with the lug and a second pivot pin 45 is formed on a stud secured in the lug 43, the pin 45 facing the pin 42 and being coaxial with and spaced from the same.

The foot 44 has a radial inward extension provided with a threaded perforation 36 into which is secured a conductor 37 leading to the other terminal of the lamp concealed under the dome 40.

A mercury tube cradle generally indicated by the numeral 50 comprising vertical side members 46 and 47 of resilient material, preferably 35 spring metal such as brass or the like, and horizontal top and bottom members 48 and 49 of insulating material such as bakelite or the like, is pivotably supported on the pins 42 and 45 40 which enter appropriate perforations in the side members 46 and 47. The four members 46, 47, 48, and 49 are rigidly secured together by suitable means such as screws, bolts or rivets 51. The side members have integral curved spring clamps 45 52 and 53 extending to the right and left respectively (Figure 3) to receive and hold a mercury switch tube of glass 54 embraced there-between. The clamps 53 are shown broken away for simplicity in Figure 2.

The mercury switch tube 54 of any suitable type is hermetically sealed and substantially evacuated of air, contains a liquid mass of metallic mercury 55 of appropriate volume and has two spaced parallel rod-like electrodes 56 and 57 50 55

sealed into the glass wall of one end of the tube. The clamps 52 are formed to clasp and hold under gentle pressure the body of the tube 54. The clamps 53 are formed to press against the exterior ends of the electrodes 56 and 57 and may, if desired, be soldered thereto for better assurance of electrical contact therewith.

A short upstanding lever arm 60 of insulating material is rigidly secured to the outer face of the side member 47 of the cradle 50 by rivets 61 and a block 62 is pivotally mounted in the upper end of the lever arm 60 by means of an integral pin 63 journaled in the arm. One end of an actuating rod 64 is secured at right angles to the pin 63 in the block. The other end of the rod 64 is pivotally attached to a short lever arm 65 mounted on a shaft 66 rigidly attached to and rotated by the swinging leaf 67 of a hinge supporting a swinging part of the door 68 of the telephone booth, the other leaf of the hinge being stationarily secured to the door frame not shown. The rod 64 is preferably threaded into the block 62 to permit of adjusting the angular relations of the cradle 50 and the door 68.

In operation, the parts being disposed as shown in Figure 1 with the door of the booth open, the tube 54 is in the position shown in full lines in Figure 3 in which the gap between the electrodes 56 and 57 is not closed by the mercury and consequently current from the supply cable 30 does not pass via conductors 37 and 38 to the lamp concealed under dome 40. When the door is closed thus rotating the lever 65 in the direction of the arrow the push rod 64 tilts the cradle 50 into the position shown in dotted lines in Figure 3, the mercury flows down to the left hand end of the tube 54 (Figure 3) and bridges the gap between the electrodes 56 and 57 thus closing the lighting circuit and lighting the lamp. As an auxiliary feature, the contact plate 33 having a perforation 39 is also mounted on the ring 22. A conductor 69 mounted in the perforation 39 is in contact with the same terminal of the concealed lamp as the conductor 37. Thus the conductor 69 is in effect connected to the conductor 37. A conductor 70 may be secured to the plate 33 by a clamp screw 71, and a conductor 72 may be secured to the plate 35 by the clamp screw 73. The two conductors 70 and 72 may then be led to another lamp or fan or other electrical device and attached to the terminals thereof when such device will be connected in parallel with the first or principal lamp across the terminals 56 and 57 and so will also be controlled

by the mercury switch and hence by the door 68. The apparatus of the invention thus provides simple, durable and reliable means for controlling a light and/or any other desired electrical device such as a fan for instance, associated with a telephone booth, closet or the like and actuated by a door.

The embodiment of the invention herein disclosed is illustrated merely and may be modified and departed from in many ways without departing from the spirit and scope of the invention as pointed out in and limited solely by the appended claims.

What is claimed is :

1. In an electrical switch device comprising a tiltingly operable circuit making and breaking device having a relatively frangible hollow glass body and two metallic electrodes extending through a wall of the body, a cradle comprising a base of insulating material, a pair of terminal members of metal mounted thereon, a pair of metal side members each tiltably mounted on one of the terminal members, each side member comprising a main portion and a body clamping member extending from the main portion in one direction and an electrode contacting member extending from the main portion in another direction, the two body clamping members being formed and disposed to receive and hold the frangible body therebetween and the two electrode contacting members being formed and disposed to each engage one of the electrodes.

2. In an electrical switch device comprising a tiltingly operable circuit making and breaking device having a relatively frangible cylindrical hollow glass body and two metallic electrodes extending through a wall of the body, a cradle comprising a base of insulating material, a pair of terminal members of metal mounted thereon, a pair of metal side members each tiltably mounted on one of the terminal members, each side member comprising a main portion and a body clamping member extending from the main portion in one direction and an electrode contacting member extending from the main portion in another direction, the two body clamping members being formed and disposed to receive and hold the frangible body therebetween under a relatively high degree of pressure and the two electrode contacting members being formed and disposed to each engage one of the electrodes under a relatively low degree of pressure.

MILES L. SVIKHART.
